US00D736818S

(12) **United States Design Patent**
Trabona et al.

(10) **Patent No.:** **US D736,818 S**
(45) **Date of Patent:** **** Aug. 18, 2015**

(54) **DISPLAY SCREEN WITH GRAPHICAL USER INTERFACE**

(71) Applicant: **Microsoft Corporation**, Redmond, WA (US)

(72) Inventors: **Denise Michele Trabona**, Seattle, WA (US); **Ethan Nelson Ray**, Lynnwood, WA (US); **Jonathan Eric Gleasman**, Seattle, WA (US)

(73) Assignee: **Microsoft Corporation**, Redmond, WA (US)

(**) Term: **14 Years**

(21) Appl. No.: **29/449,141**

(22) Filed: **Mar. 14, 2013**

(51) LOC (10) Cl. **14-04**

(52) U.S. Cl.

USPC **D14/487**

(58) **Field of Classification Search**

USPC D14/485, 486, 487, 488, 489, 490, 491, D14/492, 493, 494, 495; 715/702, 703, 715, 715/786, 835, 836, 733, 753, 757, 763, 764, 715/772, 781, 810, 837, 855, 737, 752, 708, 715/736, 739, 700, 704, 727; D18/24, 25, D18/26, 27, 28, 29, 30, 31, 32, 33; D19/1, D19/6, 8, 52; D20/11, 23, 37; D21/324, D21/325, 326, 327, 328, 329, 330, 331, 332, D21/333

CPC G06F 3/048

(74) Attorney, Agent, or Firm — Banner & Witcoff, Ltd.

(57) **CLAIM**

The ornamental design for a display screen with graphical user interface, as shown and described.

DESCRIPTION

The FIGURE is a front view of a display screen with graphical user interface showing our new design.

The broken line showing of the text and the remainder of the user interface and display screen is for environmental purposes only and forms no part of the claimed design.

1 Claim, 1 Drawing Sheet
